UNITED STATES PATENT OFFICE

JAMES MONNESE TITCOMB, OF WASHINGTON, DISTRICT OF COLUMBIA

BATCH DIVIDING AND COVERING MEANS

Application filed March 16, 1931. Serial No. 523,134.

The invention primarily has for its object to provide novel means for separating and covering certain of various materials such as gravel, sand and cement, being transported in composite batches.

I am aware that truck bodies have been provided which are equipped with dividers or partitions to enable the transporting of different materials in the separated compartments. It is the object of my present invention however to provide means enabling the transporting of a batch of materials in each such divided compartment, each batch comprising several individual materials in the proportions suitable for an ultimate mix, for example, of gravel, sand and cement. Because of the usual damp nature of the sand and the well known characteristics of the cement it must of necessity be separated from the sand to retain it in a dry state. Furthermore, it is impractical to transport cement in bulk without a covering to prevent this finely powdered material being taken up into the air, especially on windy days, and in fact in most cities this manner of transporting cement is forbidden by regulations.

Therefore in its more detailed nature the invention resides in the provision in a transporting body of a flexible sheet connected at one edge to a wall of the body and adapted to lie horizontally in the body for the purpose of separating layers of material in the body, said sheet being otherwise free so as to permit free dumping of the layers of material, and means to cover the material separated by the sheet.

The invention further comprehends a novel overlapped relation of the edges of the separating sheet and the covering means which acts in conjunction with the restraining influence of adjacent body wall portions to effect a pressure sealing of the separated material.

Other objects will in part be obvious and in part be pointed out hereinafter.

To the attainment of the aforesaid objects and ends, the invention still further resides in the novel details of construction, combination and arrangement of parts, all of

which will be first fully described in the following detailed description, then be particularly pointed out in the appended claims, reference being had to the accompanying drawings, in which:—

Figure 1 is a somewhat diagrammatic side elevation illustrating the invention applied on a dump truck body, parts being broken away and in section.

Figure 2 is a vertical cross section of the truck body.

Figure 3 is a detail fragmentary perspective view of a portion of one of the body dividers with the separating and covering sheets secured to its upper edge.

Figure 4 is a somewhat diagrammatic perspective view illustrating a pair of sheets releasably secured along their otherwise free edges.

Figure 5 is a detail perspective view illustrating a modified means for connecting the separating sheet to the body wall.

Figure 6 is a somewhat diagrammatic perspective view illustrating another means, for releasably securing the edges of the separating sheet and the covering means.

Figures 7, 8 and 9 are detail vertical longitudinal sections illustrating modified arrangements of the separating and covering sheets.

Figure 10 is a vertical cross section taken on the line 10—10 on Figures 7 or 8.

Figure 11 is a detail cross section illustrating a further modified form of separator sheet connecting means.

In the drawings I have shown so much of a truck and its dump body as is necessary to illustrate the application of the invention. The invention is mountable on any conventional form of such truck and since the body elevating mechanism forms no part of the invention it is not shown.

The truck chassis 1 is supported on wheels 2 in the usual manner and the customary cabin is indicated at 3. The body sills 4 are connected pivotally as at 5 upon the chassis beams 1 in the customary manner and support the body 6 which is equipped as usual with the rear dump gate 7 swingably connected to the body at 8.

Batch divider plates or walls 9 are positioned at spaced intervals across the body to divide it into a plurality of batch receiving compartments and the said members 9 are swingably mounted on the body side walls as at 10. These members 9 normally seat in and are held to position by floor seats 11 and when it is desired to dump a batch, the body 6 first having been raised on its pivot 5, it is only necessary to manipulate the respective handle or crank 12 to cause the eccentric hub 13 in which the pivot cross shaft 10 is secured to engage the top face of the body side and elevate the member 9 out of the seat 11 to enable it to swing on the said shaft 10.

The parts thus far described are all conventional and their detailed construction and manner of operation is well understood to workers in the art. The invention resides in combining with these parts the covering and separating sheets which I am about to describe.

Associated with each batch compartment is a plurality of separating and covering sheets, preferably of waterproof canvas. In the drawings I have shown two, one indicated 14 to separate the cement from the layer of sand, and another 15 to cover over the layer of cement.

30 The sheets are larger than the horizontal cross sectional area of the respective compartments to enable them to be lapped down into the compartments to their respective places and to assure thorough covering and separation of the cement layer, and the said sheets are secured along one edge as at 17 to the respective wall 9 or the solid end wall of the body so that they will remain attached and will not interfere with the passing out 35 of the materials as the body is dumped. The compartments may, of course, be dumped collectively but it is preferred that they be discharged from rear to front one by one, the door 7 being the first to release its batch.

40 45 In this manner the layer of cement is separated from the moist sand below and covered-protected against blowing and moisture from above.

In some instances it may be desired to temporarily secure the otherwise free edges of the sheets or flaps to completely encase the cement in envelope fashion. One convenient way of accomplishing this is to provide the three otherwise free edges of the associated 50 sheets with the well known "Zipper" fasteners diagrammatically indicated at 18 in Figure 4. In this manner the sheet edges may be joined about the cement while in transit to completely encase it as a waterproof envelope, and the "Zipper" quickly released just before dumping to free the sheet edges so that they will not interfere with the dumping of the respective batches.

60 65 If desired the separator sheet alone may be connected to the dump body partition wall as

indicated in Figures 5, 7 and 10. In these figures the separator sheet is designated 19 and is connected by straps 20 to the body partition wall 21. The cement covering means is in the nature of a free cover sheet 22 having its edges tucked into frictional overlapping engagement with those of the separator sheet in proximity to the adjacent dump body walls as indicated at 23 so that the pressure of the 70 encased cement will force them against said 75 walls and into intimate sealing contact.

When the separator and covering sheet edges are arranged in engagement as indicated in Figures 1, 2 and 6 said edges may be secured, if desired, by fastening devices as 80 indicated at 24 in Figure 6. Any suitable form of fastener may be employed but I prefer to use fasteners capable of holding the edges together during transit but which are capable of automatic separation when subjected to the strain of the weight of the cement when the body is dumped. In order to accomplish this all of the fasteners, or only those toward the dump end of the truck, may be of the automatically releasable type as 90 desired. In order to further facilitate this automatic dumping feature the separator sheet may be slit and overlapped as at 25 to provide a free discharge flap.

95 In Figure 8 of the drawings I have shown a modified form of the invention in which a single sheet 26 is employed which forms the separator sheet and is folded upon itself to form the cover sheet 27, the edges being disposed in overlapped relation as at 28 in proximity to the truck body walls as hereinbefore described. The fold joining the cover and separator sheet portions may be connected by straps 29 to the adjacent partition as 100 shown.

105 It is desirable, but not necessary, that the cover sheet be in contact with the separator sheet. In Figure 9 I have indicated a cover sheet 30 removably connected in any approved manner to the truck body walls and 110 spaced above the separator sheet but still co-operating in the material desired separation and covering function.

115 It will be readily understood that when the separator and cover sheets are edge engaged as shown in Figures 1, 2, 6, 7, 8 and 10, the material separating and covering function will be performed in the desired manner and yet, when the truck body is dumped, the separated material is free to force its way out between the sheets without the necessity of an attendant first releasing any securing means.

120 125 If desired, the connecting straps 20 may be secured to the horizontal portion only of the separator sheet 19 as indicated at 31 in Figure 11. This arrangement makes it possible to tuck the cover sheet 22 into edge-to-edge engagement with and outside of all of the upturned edges of the separator sheet. In this manner the overlying edges of the cover sheet 130

act as a complete water shed for protecting the cement encased between the sheets 19 and 22.

This application is a continuation in part 5 of my copending application of like title filed by me on May 7, 1929, Serial Number 361,053.

From the foregoing description, taken in connection with the accompanying drawings, it is thought that the novel details of construction, the manner of use and the advantages of the invention will be readily apparent to those skilled in the art to which it relates.

What I claim is:

15 1. The combination with a dump truck body including a bottom, side walls, a front wall, and a rear wall, defining a material receiving compartment, said rear wall being movable when the body is to be dumped to 20 permit egress of material from the compartment; of a flexible separator sheet attached at one edge to the front wall and being of an area sufficient to separate upper and lower layers of material and adapted when the 25 truck is dumped to permit free egress of the layers of material while remaining attached to said front wall, and a cover sheet covering over the upper layer of material and having frictional engagement with the edges of the separator sheet to cooperate therewith in completely encasing said upper layer of material.

2. In a dump truck body, a bottom and 35 walls defining a chamber for receiving a plurality of layers of material, one said wall being removable when the truck body is dumped, a flexible separator sheet having an area in excess of the area of the bottom whereby it may lie horizontally across the 40 chamber and serve to completely separate an upper layer of material from a lower layer of material, means to connect the separator sheet to the wall remote from the removable wall to retain the separator sheet in the 45 chamber when the truck body is dumped and the layers of material discharged therefrom, and a free cover sheet tucked in around its edges in frictional contact with the separator sheet edges to form therewith an envelope completely encasing the upper layer of material.

3. In a dump truck body, a bottom and 55 walls defining a chamber for receiving a plurality of layers of material, one said wall being removable when the truck body is dumped, a flexible cover and separator sheet folded over upon itself to form lower separator and upper cover sheets each of an area in excess of the horizontal cross sectional area of the chamber whereby they may 60 respectively completely separate an upper layer of material from a lower layer of material and completely cover said layer with the edges of the sheets in frictional contact for completely encasing said separated and

covered layer of material, and means to connect said flexible cover and separator sheet at its fold to the wall opposite the removable wall for the purpose described.

4. The combination with a dump body for 70 transporting segregated materials having a bottom and walls defining a rectangular material receiving hollow, of a plurality of rectangular material separating and covering sheets of flexible material connected at one edge only to a wall of the truck body adjacent the upper edge of said wall, said sheets each being of an area in excess of the horizontal cross sectional area of the truck body hollow to enable them to be lapped down into the body hollow varied distances and thence into frictional edge-to-edge contact whereby to provide for a complete encasement of the material while in transit and yet permit free dumping of the encased material without the necessity of sheet edge releasing manipulation.

5. The combination of a dump body having side walls, a rigid end wall, swingable batch dividing and dumping walls, and a dumping end gate forming a plurality of batch compartments; of a plurality of sets of rectangular material separating and covering sheets of flexible material, the sheets of each set being connected at one edge only to the end wall or one of the dividing walls and each being of an area in excess of the horizontal cross sectional area of the associated batch compartment to enable them to 90 be lapped down into the respective batch compartments varied distances and then into frictional edge-to-edge contact whereby to provide for a complete encasement of the material while in transit and yet permit free dumping of the encased material through the associated dividing walls and end gate without the necessity of sheet edge releasing manipulation.

6. In a dump truck body, a bottom and walls defining a chamber to receive a plurality of layers of material, one said wall being removable when the truck body is dumped, a flexible separator sheet having an area in excess of the area of the bottom whereby it may lie horizontally across the

chamber and serve to completely separate an upper layer of material from a lower layer of material, means to connect the separator sheet to the wall remote from the removable wall to retain the separator sheet in the chamber when the truck body is dumped and the layers of material discharged therefrom, and a free-edged cover sheet overlapping upturned edges of the separator adjacent the chamber defining walls whereby the upper layer of material will be encased by said sheets and will press the overlapped edges of the sheets into intimate material sealing contact while permitting 115

free egress of the encased material when the truck body is dumped.

7. The combination with a dump body for transporting segregated materials having a bottom and walls defining a rectangular material receiving hollow, of a plurality of rectangular material separating and covering sheets of flexible material connected at one edge only to a wall of the truck body adjacent the upper edge of said wall, said sheets each being of an area in excess of the horizontal cross sectional area of the truck body hollow to enable them to be lapped down into the body hollow varied distances and into frictional edge-to-edge contact whereby to provide for a complete encasement of the material while in transit, and means to releasably secure the contacting edges of the sheets for the purpose specified.

20 8. In a dump truck body, a bottom and walls defining a chamber to receive a plurality of layers of material, one said wall being removable when the truck body is dumped, a flexible separator sheet having an area in excess of the area of the bottom whereby it may lie horizontally across the chamber and serve to completely separate an upper layer of material from a lower layer of material, means to connect the separator sheet to the wall remote from the removable wall to retain the separator sheet in the chamber when the truck body is dumped and the layers of material discharged therefrom, and a free-edged cover sheet overlapping upturned edges of the separator sheet adjacent the chamber defining walls whereby the upper layer of material will be encased by said sheets and will press the overlapped edges of the sheets into intimate material sealing contact while permitting free egress of the encased material when the truck body is dumped, said cover sheet being connected to the separator sheet along its edge remote from the removable wall so that it will remain with the separator sheet in the chamber when the layers of material are dump-discharged therefrom.

50 9. The combination with a dump truck body including a bottom, side walls, a front wall and a rear wall defining a material receiving compartment, said rear wall being movable when the body is to be dumped to permit egress of material from the compartment; of a flexible separator sheet attached at one edge to the front wall and being of an area sufficient to separate upper and lower layers of material and a cover sheet of an area for completely covering the separated layer of material and being connected to the separator sheet along its edge nearest the front wall, said separator and cover sheet edges frictionally engaging to encase the separated layer of material, and means to constrain the engaged edges against separating during transit of the truck body but auto-

matically releasable when the truck body is dumped to permit free egress of the encased layer of material.

10. The combination with a dump truck body including a bottom, side walls, a front wall and a rear wall defining a material receiving compartment, said rear wall being movable when the body is to be dumped to permit egress of material from the compartment; of a flexible separator sheet attached at one edge to the front wall and being of an area sufficient to separate upper and lower layers of material and a cover sheet of an area for completely covering the separated layer of material and being connected to the separator sheet along its edge nearest the front wall, said separator and cover sheet edges frictionally engaging to encase the separated layer of material, and means for securing the engaged edges during transit of the truck body but automatically releasable by strain of the weight of the encased material when the truck body is dumped for automatically releasing the encased material.
